UNITED STATES PATENT OFFICE

169,047

GLOVE

Lorin B. Sebrell, Dover, Del., assignor to International Latex Corporation, Dover, Del., a corporation of Delaware

Application November 7, 1952, Serial No. 22,191

Term of patent 14 years

(Cl. D3—11)

To all whom it may concern:

Be it known that I, Lorin B. Sebrell, a citizen of the United States and a resident of Dover, Delaware, in the county of Kent and State of Delaware, have invented a new, original, and ornamental Design for a Glove, of which the following is a specification, reference being had to the accompanying drawing, forming part thereof, wherein:

Fig. 1 is a rear view of a glove, showing my new design;

Fig. 2 is a side elevational view thereof; and Fig. 3 is a front view thereof.

I claim:

The ornamental design for a glove, as shown.
LORIN B. SEBRELL.
